(57) **CLAIM**

The ornamental design for a simulated bamboo and wicker chair, as shown and described.

DESCRIPTION

FIG. 1 is a front elevational view of a simulated bamboo and wicker chair showing our new design;
FIG. 2 is a rear elevational view thereof;
FIG. 3 is a right side elevational view thereof, the left being a mirror image thereof;
FIG. 4 is a perspective view thereof;
FIG. 5 is a top plan view thereof; and,
FIG. 6 is a bottom plan view thereof.
